NEAL GARRETT, OF BERKELEY, CALIFORNIA.

CONCRETE WALL CONSTRUCTION.

Application filed November 13, 1924. Serial No. 749,689.

The present invention relates to improvements in concrete wall construction, and has particular reference to convenient means for erecting forms for a concrete structure. It is particularly contemplated to provide easily manipulated collapsible forms for hollow wall structures and particularly for such structures in which concrete is sprayed or plastered against the face of a wooden form. It is further proposed to provide means whereby concrete studdings for the hollow walls may be made integral with the walls and completed in one continuous spraying or plastering operation. It is further contemplated to provide means allowing the hollow form of a house to be built up at one time so that the whole spraying or plastering operation for the whole house may be performed without interruption. In this specification, the term concrete is used to include adobe, plaster, stucco, cement, cement stucco, molten silica, etc.

Further objects and advantages of my device will appear as the specification proceeds.

The preferred forms of my device are illustrated in the accompanying drawings, in which—

Fig. 1 shows, in isometric representation, one arrangement of forms using pre-cast pillars for studdings;

Fig. 2 a vertical section through the same;

Fig. 3 an isometric detail view of a holding member for spacing bars;

Fig. 4 a top plan view of a modified arrangement;

Fig. 5 an isometric view of a modified corner arrangement;

Figs. 6, 7 and 8, top plan views of further modifications;

Fig. 9 an isometric view illustrating an arrangement by which interior wall and ceiling may be applied in one operation;

Fig. 10 a form containing a window form, and

Figs. 11 and 12 views explaining a further modification.

In the drawings, the vertical scale has been greatly reduced. The walls referred to in this specification are of the proportions of those used in ordinary building construction.

While I have shown only a limited number of modifications in the drawings, it should be understood that still further modi-

fications may be made without departing from the spirit of the invention.

In the form illustrated in Fig. 1, I provide a base 1 resting either on the foundation or on the bare ground or possibly on an underlying wall. On top of this base lie in spaced and parallel relation two runners 2, having nailing strips 3 secured thereto. Between the two runners and their respective nailing strips, I provide a number of columns or pillars 4 arranged to occupy transversely the whole space between the runners. Above each pillar I arrange a casting 6 preferably of metal and formed to project outside of the pillar to provide pockets 7 in which spacers 8 are received, the latter being disposed to have their inner faces in the same plane as the inner faces of the runners 2. The forms 9 are preferably made to fill the space between two pillars in the manner indicated in Fig. 1, and two forms are introduced between each set of pillars. A wedge 11 with a suitable handle 12 is introduced between the two forms and when suitably manipulated forces the two forms apart so that the edges thereof rest against the spacers and the runners respectively. A wire netting 13, or any other suitable reinforcing means, may be nailed to the strip 3 and the spacers 8 at a distance from the pillars and the outer faces of the forms 9 and the pillars are preferably provided with any suitable means 14 connecting the wire netting to the pillars. The forms 9, and all other forms referred to in this specification, must have their surfaces covered with paper, oil, or some other material to keep the concrete from sticking to them.

The manner of using this arrangement is readily understood. After the pillars 4 have been erected on the base 1 and the runners 2 have been placed in their proper positions, the spacers 8 are introduced and engaged with the holding members 6 in the manner illustrated in the figure. The two forms 9 are then introduced between each set of pillars and forced apart by means of the wedge 11 so that the upper and lower edges of the forms rest against the spacers and the runners respectively, and the outer faces of the forms are substantially flush with the outer faces of the pillars. Previously prepared concrete is now applied to both outer surfaces so as to firmly unite with the wire netting 13, or whatever reinforcing means has

- been selected, and is allowed to set. After the time for setting has expired, the wedges 11 are turned by means of the handle 12 and the forms 9 are allowed to or made to collapse inwardly whereupon they may be withdrawn. The spacers and the holders for the spacers may now also be removed and forms and spacers may be used over again for a second operation.
- 10 In the variation shown in Fig. 4, two sets of forms 14 and 16 are used between two neighboring pillars and the forms of one set are provided with inward projections 17 which serve as stops for a modified wedge 18.
- 15 In Fig. 5 is shown the arrangement used for a corner if it is desired to cast two sides of the house in one operation. In that case it is necessary to lay one set of spacers 19 on top of a second set of spacers 21 in the manner illustrated in the figure and to compensate for the higher elevation of the spacers 19, the pillars 22 supporting the holders for the latter spacers have a block 23 interposed between the top of the pillar and the holder for the spacer so as to allow pillars of the same size to be used all around the house. It will be noted that at the inner joint, the corners for the forms have to be cut away as shown at 24 to accommodate the spacer which would otherwise be in the way.
- 19 Fig. 6 shows that instead of, or in addition to, the elements already described for engagement with edge portions of the outer faces of the forms, the pillars, columns, or studs 31 may be provided with flanges 32 against which a shoulder 28 of the forms 26 may be wedged. To eliminate a crack between the flanges 32 and the outer face of the form 26, the form preferably should be provided with yielding flaps 29. The forms 26 are held in spaced relation by the wedge 27, according to the principle previously outlined, and with these exceptions the forms 26 and the columns 31 perform identically the same functions as the forms 9 and the columns 4 of Fig. 1.
- 20 Similar forms and columns may be used to cast slabs not in other than vertical position for roofing and the like.
- 24 In Fig. 7 is shown an arrangement allowing studdings to be cast or formed simultaneously with the sides of the hollow wall so that no pre-cast pillars are necessary. The two forms 34 which are held in spaced relation, according to the principles previously outlined, by means of the wedge 36 are cut away at their outer edges, as shown at 30, and preferably provided with tin flaps 30' extending over the cut-out portions. Two adjacent arrangements of this character are made to leave a gap 31' between the same and the space between the two forms of one unit is preferably closed against the gap by means of the springs 33

engaging with the reduced edges 34 of the forms and tending to force the same together. While the forms are sprung apart by the wedges 36, the springs serve as a separating wall between the gap 31 and the spaces between the forms. The concrete may now be applied to the outer faces of the forms and the spray may at the same time be directed against the gap, preferably first at an angle from the left hand side, as viewed in Fig. 7, so as to provide a heavy coat on the face of the right spring 33 and then from the right hand side to form a heavy coat on the left member 32 until gradually the whole gap is filled up and forms a studding or pillar integral with the concrete walls. This method can be used also with hand-placed mortar.

25 After the concrete has been applied in this manner and has set, the spring member 33 serves to collapse the two forms inwardly as soon as the wedge 36 is released.

26 In the modification shown in Fig. 8, regular angle irons 37 are used to define the gap.

27 In Fig. 9 is shown in isometric view an arrangement for applying the ceiling and walls in one continuous operation. Transverse joists 38 are placed on the pillars 39 in the manner shown, whereby slots 41 in the joists may be made to register with reinforcing elements 42 extending upwardly from the pillars. The members 38 do not necessarily represent joists but may be beams supporting a roof. A wire netting 43 is suspended from the joists 38 by means of rods 44 and the wire netting may be made to join the wire netting for the inner wall, as shown at 46, so that the inner wall and ceiling may be applied in one operation. It will be readily understood, of course, that in a similar manner the whole building might be constructed in one single operation.

28 Where it is desired to provide an opening of any shape a simple frame 47 corresponding to the opening desired, may be secured to the form 9 in the manner illustrated in Fig. 10, and may be knocked down after the concrete surrounding the same has set. A wire 40 may be tied around the outside of, but not attached to, the frame 47, and may be used for securing the ends of the reinforcing wire netting thereto.

29 In Figs. 11 and 12 is shown a further modification allowing of the construction of a hollow wall with studdings formed integral therewith in two operations. The members 48 of these views correspond to the spacing members previously described and are supported similarly, preferably with vertical rods 49 provided opposite those places where the studdings are to be placed. Forms 51 are secured between the spacing bars 49 and runners disposed underneath the same, as shown in Fig. 1, the confronting edges of the forms being spaced to provide gaps 52.

Ordinarily boards 53 are squeezed between the spacing member on one side and the form so as to force the latter toward the other spacing member, and the boards 53 are 5 preferably arranged so as to narrow the gap as shown at 54. One side of the wall may now be sprayed or plastered, the concrete entering the gap 52 and the reduced gap 54, so that at the end of the operation, one side 10 is cast and a part of the studding, as shown in Fig. 12. Thereupon the forms 51 are shifted over to the other side and the boards 53 now force the latter against the opposing spacing members 48, with a gap left between the confronting edges of the same 15 registering with the partly cast studdings. The operation is now completed by applying concrete to the outer faces of the forms and by filling up the gap whereby the material 20 is directed against the partly cast studding.

The advantages of this manner of constructing a house are apparent. The forms may be arranged to allow of the whole house 25 to be completed in one operation and the forms may be used over and over again for successive building operations. The forms may be shaped to any kind of architecture, adapt themselves readily to round or curved 30 walls and it is not necessary that houses built by means of the same forms show monotonous repetition in construction. The concrete may be thrown or sprayed against the outer faces of the forms in such a manner as to leave the desired surface and as not 35 to require any finishing. If finishing is desired, the method outlined offers a superior finishing surface as compared with surfaces offered by concrete form against a removable mold. My method also provides for 40 a lighter wall for a given amount of material and a given strength than any other method in use known to me.

The structure, of course, offers all the advantages of double wall construction providing an air space between the two sides of wall which forms insulation for heat and dampness.

I claim:

50 1. Means for erecting concrete structure comprising two forms and means for holding the same in spaced relation comprising elements made for engagement with edge portions of the outer face of the forms and means engaging with the inner faces for forcing the outer faces upon the said elements.

55 2. Means for erecting concrete structure comprising two forms and means for hold-

ing the same in spaced relation, comprising 60 elements made for engagement with edge portions of the outer faces of the forms and means engaging with the inner faces for forcing the outer faces upon the said elements, the latter means being removable to 65 allow the forms to be collapsed inwardly when concrete applied to the outer faces has set.

3. Means for erecting concrete structure 70 comprising two sets of spaced elements disposed in vertically spaced relation, a pair of forms adapted to be inserted between the elements of the two sets and means engaging with the inner faces of the forms for forcing the same outwardly against the ele- 75

4. Means for erecting concrete structure comprising two sets of spaced elements disposed in vertically spaced relation, a form 80 adapted to be inserted between the elements of the two sets and means utilizing corresponding elements of the sets for bracing adapted to force the form upon the other elements.

5. Means for erecting concrete structure 85 comprising a base, runners mounted thereon in spaced relation, pillars supported on the base between the runners having spacing bars supported relative thereto in vertical alinement with the runners and forms adapted for insertion between the spacing bars and the runners having means associated therewith for spreading the same apart for contacting engagement with the spacing bars and the runners. 90 95

6. Means for erecting concrete structure comprising a base, runners mounted thereon in spaced relation, pillars supported on the base between the runners having spacing bars supported relative thereto in vertical alinement with the runners, forms adapted for insertion between the spacing bars and the runners and wedges made for insertion between the forms for spreading the same apart into contacting engagement with the spacing bars and the runners. 100 105

7. Means for erecting concrete structure comprising a base, runners mounted thereon in spaced relation, pillars supported on the base between the runners having spacing 110 bars supported relative thereto in vertical alinement with the runners and a form adapted for insertion between the spacing bars and the runners having means associated therewith for forcing the same into 115 contacting engagement with one of the runners and the corresponding spacing bars.

NEAL GARRETT.
